COMBINATION LOCK.

APPLICATION FILED JULY 16, 1915.

1,240,114.

Patented Sept. 11, 1917.

Fig. 1.

UNITED STATES PATENT OFFICE.

JACOB BAUM, OF CINCINNATI, OHIO; ANNA WILLIAMS BAUM, MARY BAUM BIRNBRYER, GEO. M. BACON, AND JOSEPH B. DERBES, EXECUTORS OF SAID JACOB BAUM, DECEASED.

COMBINATION-LOCK.

1,240,114.

Specification of Letters Patent. Patented Sept. 11, 1917.

Application filed July 16, 1915. Serial No. 40,240.

To all whom it may concern:

Be it known that I, JACOB BAUM, a citizen of the United States, and a resident of Cincinnati, in the county of Hamilton and State 5 of Ohio, have invented certain new and useful Improvements in Combination-Locks, of which the following is a specification.

My invention relates to locks; and its object is to facilitate and render more secure 10 the fastening of the inner disks in the tumbler wheels, and to simplify the construction of the inner disks and other parts of the lock.

My invention consists in the combination 15 of parts and in the details of construction and arrangement of parts as will herein be more fully described and claimed.

In the drawing:

Figure 1 is a vertical section through the 20 tumbler wheels and their mounting;

Fig. 2 is a similar view of one of the tumbler wheels of modified construction;

Fig. 3 is a detail of the fastening ring;

Fig. 4 is a front elevation, and Fig. 5 25 is a rear elevation of one of the tumbler wheels.

The back plate 1, has, projecting forwardly into the lock, the hollow stud 2 upon which stud the tumbler wheels 3 are rotatably mounted with washers 4 interposed 30 between them, and with a washer 5 interposed between them and the back plate 1. The washers 4 have lugs 6 projecting into a longitudinal keyway 7 on the exterior of 35 the hollow stud 2. Near its forward end, the hollow stud 2 has an annular groove 8, into which is sprung a ring 9 that prevents the tumbler from forward displacement from the hollow stud 2.

The back plate 1 is made up of a forward 40 section 1' and a rear section 1'' with the hollow stud 2 pressed forward from the section 1', these sections being made of sheet metal, and the structure thus being in two 45 pieces joined together instead of an integral cast structure as commonly used.

The front section 1' of the back plate is formed up with its peripheral part consisting 50 of a flat radially extending flange 1^a and an outer or peripheral shell 1^b, which joins the hollow stud 2 through an intermediate part 1^c that is pressed backward in the form of an annular channel of substantially semi-circular cross section, which is of diameter 55 somewhat less than the distance between the

shell 1^b and hollow stud 2, so that annular plane parts 1^d and 1^e are left around the center and near the periphery, respectively, to form the front surfaces of the back plate. The part 1^d forms a bearing for the washers 60 5. The outer shell 1^b forms the bearing for the back plate in the aperture inside of the safe door or lock case into which such locks are fitted in a well-known manner, and the flange 1^a serves to attach the forward section 1' to the rear section 1'', which latter section is merely a disk of sheet metal with 65 its edge 1^f turned forward over the flange 1^a and pressed tightly down thereon. Thus the back plate is formed with a radially 70 extending peripheral flange made up of three thicknesses of the sheet metal, and thus of ample thickness to afford the required strength for securing the back plate to the safe door by a fastening means passing 75 through openings 1^g in this flange. The hollow stud 2 may have its keyway 7 and the annular groove 8 pressed in it.

Each tumbler wheel 3 comprises the main outer disk 10 and the inner disk 11 fitting 80 into a central aperture of the main outer disk, the wall of the aperture and the periphery of the inner disk having teeth 12 that mesh and cause the two disks to turn together, but allowing the inner disk to be 85 slipped out and reinserted in as many different positions relative to the outer disk 10 as there are teeth 12. As is well known, it is by this means that the combination of 90 the lock is changed. I simplify the operation of changing the combination of the lock, and at the same time render secure the fastening of the inner disk in the outer disk, by providing a fastener 13 made of a piece of resilient wire bent into an incomplete circle and sprung into an annular groove 14 formed in a reduced part 15 of the periphery of the inner disk 11 directly to the rear of the teeth 12, exteriorly of the main outer disk 10. The reduced part 15 95 is of such diameter relative to the diameter of the outer circle of the teeth 12, and the groove 14 is of such depth, that the ring 13 will project out all around and engage with the main outer disk 10 of the tumbler wheel 100 around the rear sides of the teeth of the tumbler wheel and be easily pried from its groove when desired. Thus the ring may be very strong and unyielding to side thrust 105 of the disks 10 and 11 relative to each other. 110

With the groove 14 thus provided, the inner disk 11 is inserted through the central aperture of the main outer disk 10. As shown in Fig. 1, the toothed periphery of the disk 11 and toothed wall of the aperture of the disk 10 are tapered inwardly or rearwardly in such relation to each other that the inner disk 11 will stop with its outer or front side flush with the outer or front side 10 of the main outer disk 10, and the annular groove 14 will be brought into exactly the proper relation with the rear side of the outer main disk 10 around the central aperture for the resilient fastener 13 to engage 15 tightly against said rear part when sprung into the groove 14.

As shown in Fig. 2, the toothed parts are not tapered, but the toothed wall of the central aperture of the outer disk 10^a is provided with a shoulder 16 against which the rear or inner sides of the teeth on the periphery of the inner disk 11^a abut and form the stop therefor, co-operating with the fastener 13 and groove 14 as above described.

As is well known in combination lock construction, one tumbler wheel drives the other one by means of a stationary lug engaging with a movable lug on the other one. Thus, the inner disk 11 of each driving tumbler wheel has a stud 17 which engages with a movable lug 18 on each driven tumbler wheel, which movable lug is mounted on a ring 19 journaled on a central hub 20 formed by turning an annular groove 21 in the front of the disk 11 for the ring 19 to lie in. This movable lug 18 projects back through a segmental slot 22 in the disk 11, being limited in its movement by the ends of this slot, as is well known in the art.

As heretofore constructed, the studs inserted into the inner disks 11 to form the stationary lugs, must be very carefully fitted after their insertion to accurately co-operate with the movable lugs, and furthermore have the disadvantage of becoming loosened after considerable use.

To obviate these disadvantages by forming the inner disk of wrought metal, as indeed, I also form the outer main part 10 of, by 50 cutting these parts from sheet metal and pressing thereon not only the teeth, either tapered or shouldered, as shown in Fig. 1 or Fig. 2, but also pressing in the inner disk the groove 21, cutting therein the segmental slot 22, and pressing up from a slot diametrically opposite from the slot 22 therein, an integral lug 17. When the lug 17 is thus 55 pressed up, it is preferably made wide, as best shown in Fig. 5, to give it the requisite strength in circumferential direction, and this increase in width is readily compensated for by increasing the length of the segmental slot 22 and increasing the width of the movable lug 18 as seen in Figs. 4 and 5.

60 This forming of the various parts of the

lock of sheet metal by means of dies and punches obviates necessity of fitting either by machine or by hand on any of the parts, because they can all be shaped very accurately and uniformly, and are more readily 70 interchangeable than when fitted by machinery. Where hand fitting is dispensed with, the parts are made interchangeable, whereas before they were not at all interchangeable.

Having fully described my invention, what I claim as new and desire to secure by Letters Patent is:

1. In a combination lock, a tumbler wheel comprising an outer disk having a central aperture with abutting means around it, an inner disk adapted to be inserted from one side of said main outer disk and bear against the abutting means around the aperture, and having a part extending out of the opposite side of said main outer disk, this part of the inner disk having a peripheral groove lying behind the abutting means of the aperture when the inner disk is thus inserted, and resilient fastening means in said groove, to prevent displacement of said inner disk from said outer disk. 95

2. In a combination lock, a tumbler wheel comprising an outer disk having a central aperture with an axially tapered wall forming abutting means around it, an inner disk having a tapered periphery and being adapted to be inserted from one side of said outer disk and bear against the abutting means around the aperture, and having a part extending out of the opposite side of said outer disk, this part of the inner disk having a peripheral groove lying behind the abutting means of the aperture when the inner disk is thus inserted, and resilient fastening means in said groove, to prevent displacement of said inner disk from said outer disk, but accessible for the purpose of prying it out of said groove when it is desired to displace said inner disk from said outer disk. 100

3. In a combination lock, a tumbler wheel comprising an outer disk having a central aperture with an axially tapered toothed wall forming abutting means around it, an inner disk having a tapered toothed periphery to mesh with said toothed wall and being adapted to be inserted from one side of said outer disk and bear against the abutting means around the aperture, and having a part extending out of said outer disk on the opposite side of said main outer disk, this part of the inner disk having a peripheral groove lying behind the toothed wall of the aperture when the inner disk is thus inserted, and resilient fastening means in said groove, to prevent displacement of said inner disk from said outer disk, but accessible for the purpose of prying it out of said groove when it is desired to displace said inner disk from said outer disk. 115

sible for the purpose of prying it out of said groove when it is desired to displace said inner disk from said outer disk.

4. In a combination lock, a tumbler wheel comprising an outer disk having a central aperture with a toothed wall and abutting means around said toothed wall, an inner disk having a toothed periphery to mesh with said toothed wall and being adapted to be inserted from one side of said outer disk and bear against the abutting means around the aperture, and having a part extending out of the opposite side of said main outer disk, this part of the inner disk having a peripheral groove lying behind the toothed wall of the aperture when the inner disk is thus inserted, and resilient fastening means in said groove, to prevent displacement of said inner disk from said outer disk, but accessible for the purpose of prying it out of said groove when it is desired to displace said inner disk from said outer disk.

5. In a combination lock, a tumbler wheel comprising an outer disk having a central aperture with abutting means around it, an inner disk adapted to be inserted from one side of said outer disk and bear against the abutting means around the aperture, and having a part extending out of the opposite side of said outer disk, this part of the inner disk having a peripheral groove lying behind the abutting means of the aperture when the inner disk is thus inserted, and a wire bent into substantially the shape of an incomplete circle and sprung into said peripheral groove by spreading over the part of the periphery of said inner disk away from said outer disk, to prevent displacement of said inner disk from said outer disk, but accessible for the purpose of prying it out of said groove when it is desired to displace said inner disk from said outer disk.

6. In a combination lock, a tumbler wheel comprising an outer disk having a central aperture with a toothed wall, and abutting means around said toothed wall, an inner disk having a toothed periphery to mesh with said toothed wall and being adapted to be inserted from one side of said outer disk and bear against the abutting means around the aperture, and having a part extending out of the opposite side of said outer disk, this part of the inner disk having a peripheral groove lying behind the toothed wall of the aperture when the inner disk is thus in-

serted, and a wire bent into substantially the shape of an incomplete circle and sprung into said peripheral groove by spreading over the part of the periphery of said inner disk away from said outer disk, to prevent displacement of said inner disk from said outer disk, but accessible for the purpose of prying it out of said groove when it is desired to displace said inner disk from said outer disk.

7. In a combination lock, a tumbler wheel comprising an outer main part having a central aperture with abutting means around it, and an inner disk inserted into said aperture from one side of said main part against the abutting means and having a peripheral groove that lies behind the abutting means when said disk is thus inserted, and a resilient fastening means held in said groove and engaging behind the abutting means to prevent withdrawal of said inner disk from said outer main part, said inner disk having a stationary pressed-up lug formed integral therewith.

8. In a combination lock, a tumbler wheel comprising an outer main part having a central aperture with abutting means around it, and an inner disk inserted into said aperture from one side of said main part against the abutting means and having a peripheral groove that lies behind the abutting means when said disk is thus inserted, and a resilient fastening means held in said groove and engaging behind the abutting means to prevent withdrawal of said inner disk from said outer main part, said inner disk having a stationary pressed-up lug formed integral therewith.

9. In a combination lock, a back plate formed of two sections of sheet metal, one of these sections having a hollow stud pressed forward from its center, and being embossed with an outer shell and a radially extending peripheral flange, and the outer section being in the form of a disk with its outer edge turned in over this peripheral flange of the one section, whereby the outer shell of the one section forms a bearing means for the back in the safe door, and whereby the peripheral flange with the outer edge turned thereover becomes a flange for fastening the back plate into the safe door.

JACOB BAUM.
